R. S. PEIRCE

PIPE CLAMP

Filed Nov. 27, 1922

Inventor:
Ralph S. Peirce
By G. L. Clegg Atty.

UNITED STATES PATENT OFFICE.

RALPH S. PEIRCE, OF HINSDALE, ILLINOIS.

PIPE CLAMP.

Application filed November 27, 1922. Serial No. 603,432.

To all whom it may concern:

Be it known that I, RALPH S. PEIRCE, citizen of the United States, residing at Hinsdale, in the county of Du Page and State 5 of Illinois, have invented a certain new and useful Improvement in Pipe Clamps, of which the following is a full, clear, concise, and exact description.

My invention relates to clamps which may 10 be disposed about cylindrical objects such as water hose and other piping.

In the clamp of my invention there is employed a band of ribbon form which is circular in curvature and whose ends preferably overlap, though the invention is not 15 to be thus limited. This band has two outwardly extending lateral projections. One of these projections is preferably formed by folding an intermediate part of the band to 20 leave a continuation which is sufficient in extent to underly the other lateral projection whereby a completely encircling band is produced, though the invention is not to be thus restricted. One of these lateral 25 projections is preferably a conduplicate fold whose bight end is folded back toward the band, the projection at the intermediate portion of the band being preferably thus formed.

Both lateral projections of the band are 30 formed with bolt passages and one of these lateral projections is constituted to serve as a nut with which the bolt has threaded engagement.

In the preferred embodiment of the invention the inter-crown space of the bolt threads is wider than the thickness of the edge portion of the band that enters the thread space and this edge portion is preferably 35 of helical curvature conforming to the spiral of the thread. The lateral projection of the band thus formed for engagement with the thread of the bolt is preferably the one which is at the free end of the 40 band.

The invention will be more fully explained by reference to the accompanying drawing in which Fig. 1 is a view in side elevation of a clamp constructed in accordance with the preferred embodiment of the 50 invention; Fig. 2 is a perspective view of the clamp shown in Fig. 1 with the bolt omitted; Fig. 3 is a cross sectional view of my clamp somewhat modified; Fig. 4 illustrates, in elevation, the clamp of Fig. 3 with the bolt omitted; and Fig. 5 shows the spiral shap-

ing of a bolt thread engaging portion of the band.

Like parts are indicated by similar characters of reference throughout the different 60 figures.

The band 1 is oblong in cross section, being of ribbon formation. It is formed with two outwardly extended lateral projections generally indicated at 2 and 3. 65

In the form of the invention shown in Figs. 1 and 2 the projection at 3 is a four sided fold 4 of conduplicate formation, this projection 3 being the one which is preferably formed at an intermediate part of the 70 band to leave a band continuation 5 which underlies the projection 2. The bight end 6 of the conduplicate fold is folded back toward the band to enhance the rigidity of the projection 3 with relation to the band 75 that supports it.

In the form of the invention illustrated in Figs. 3 and 4 the four sided fold is of sinuous formation, the bight 7 of the two inner layers or sides of the fold being interposed between the two outer layers or sides of the fold, this bight increasing the rigidity between the circular portion of the band and its projection 3. The projection at 2 is of sinuous formation in both forms of 85 the invention, there being four layers or sides to the fold. The bight 8 of the two inner layers of the projection 2 is interposed between the two outer layers of this projection and also increases the rigidity between 90 the circular portion of the band and this projection 2. The bight at 9 between two outer layers of the projection 2 is formed to have clamping engagement with a circuit 95 wire 10, this formation being preferred when the clamp is to serve as a grounding clamp in addition to performing its mechanical function.

The projections at 2 and 3 are formed with bolt receiving holes or passages 11 and 100 12 through which the stem of a threaded bolt 13 is passed. The head of this bolt engages the intermediate projection at 3 and the threaded portion of the bolt is in threaded engagement with the projection at 2. 105

As illustrated, each layer of the fold of the projection 2 is in engagement with the bolt substantially throughout the circumference of the latter, the portion of each fold layer that engages the thread of the bolt 110 being of helical curvature at its thread engaging edge to conform to the spiral of the

thread. Where the engaging part of each fold side of projection 2 substantially circumscribes the bolt and the thread engaging edge portion of such fold is helically shaped 5 as described, at least one slot or slit 14 is formed in each fold layer to permit the thread engaging edge portion to follow the helical direction of the bolt thread.

By means of the preferred construction 10 pipe circumscribing bands of thinner material may be employed than hitherto.

While I have herein shown and particularly described the preferred embodiment of my invention I do not wish to be limited to 15 the precise details of construction shown as changes may readily be made without departing from the spirit of my invention, but having thus described my invention I claim as new and desire to secure by Letters 20 Patent the following:

1. In a clamp, the combination with a band that is oblong in cross section and has two outwardly extending lateral projections formed with bolt receiving passages there- 25 through; of a bolt passing through said passages having threads receiving an edge portion of the band and whose intercrown space is wider than the thickness of the band, the portion of the band that engages 30 the thread of the bolt being of helical cur-

vature at its thread engaging edge which conforms to the spiral of such thread.

2. In a clamp, the combination with a band that is oblong in cross section and has two outwardly extending lateral projections 35 formed with bolt receiving passages there-through; of a bolt passing through said passages having threads receiving an edge portion of the band, the portion of the band that engages the thread of the bolt being of helical curvature at its thread engaging edge which conforms to the spiral of such thread.

3. In a clamp, the combination with a band that is oblong in cross section and has 45 two outwardly extending lateral projections formed with bolt receiving passages there-through; of a bolt passing through said pas-sages having threads receiving an edge portion of the band, the projection of the band 50 that engages the thread of the bolt being sinuously folded with the outer layer of the fold in engagement with the bolt and of helical curvature at its thread engaging edge which conforms to the spiral of such thread. 55

In witness whereof, I hereunto subscribe my name this 23d day of November A. D., 1922.

RALPH S. PEIRCE.
